166,117

RANGE

James A. Nelson, Elmhurst, George W. Kamin, Lombard, and Lawrence E. Wolske, Chicago, Ill., assignors to Cribben and Sexton Company, Chicago, Ill., a corporation of Illinois

Application February 24, 1950, Serial No. 8,104

Term of patent 14 years

(Cl. D81—4)

To all whom it may concern:

Be it known that we, James A. Nelson, George W. Kamin, and Lawrence E. Wolske, citizens of the United States, residing at Elmhurst, in the county of Du Page, Lombard, in the county of Du Page, and Chicago, in the county of Cook, respectively, and State of Illinois, have invented a new, original, and ornamental Design for a Range, of which the following is a specification, reference being had to the accompanying drawing, forming a part thereof, in which:

Fig. 1 is a perspective view of a range showing our new design; Fig. 2, a view similar to Fig. 1 but showing a portion of the range in partly extended position; Fig. 3, a front view in elevation; Fig. 4, a side view in elevation; Fig. 5, a side view in elevation showing the opposite side to that shown in Fig. 4; and Fig. 6, a vertical sectional view of the back splasher.

We claim:

The ornamental design for a range, as shown.

JAMES A. NELSON.
GEORGE W. KAMIN.
LAWRENCE E. WOLSKE.
